UNITED STATES PATENT OFFICE

CHARLES H. NORTON, OF WORCESTER, MASSACHUSETTS, ASSIGNOR TO NORTON COMPANY, OF WORCESTER, MASSACHUSETTS, A CORPORATION OF MASSACHUSETTS

GRINDING MACHINE

Application filed November 8, 1920. Serial No. 422,412.

My invention relates to grinding machines and more particularly to mechanism for traversing the grinding wheel and the work relative to each other at a rapid rate.

5 In production grinding of work pieces of similar shape, the time consumed on each piece depends upon the rate at which the work is traversed past the grinding wheel. It has been found that the wheel should be 10 rotated rapidly but fed into the work slowly so as to produce a shallow cut and that the wheel should be as wide as feasible and the work traversed past it at such a rate that the wheel will just cover the work. It, however, is found that this rate of relative 15 traverse of the two heavy machine tables is limited by the amount of permissible shock and vibration incident to reversing the direction of travel of the moving body. Otherwise 20 chatter marks and other detrimental effects would appear upon the work.

It is accordingly an object of my invention to provide a grinding machine in which the work and the wheel tables may be reciprocated relative to each other at a rate heretofore considered impossible and to produce such rapid traverse without material shock and consequent detrimental grinding action.

25 With this and other objects in view, as will be apparent in the following disclosure, my invention resides in the combination of parts described in the specification and covered by the claims appended hereto.

30 In the drawings in which like reference numerals indicate like parts:

Figure 1 is a front elevation of a grinding machine for plane surfaces embodying my invention;

35 Fig. 2 is a vertical section, showing the driving mechanism partly broken away;

Fig. 3 is a detached plan view of the reversing and driving mechanism, the bearings and the supports for this mechanism 40 being omitted;

Fig. 4 is a front elevation of a portion of one type of cylindrical grinding machine embodying my invention;

50 Fig. 5 is a section partly in elevation of

the cylindrical grinding machine, showing a portion of the driving mechanism;

Fig. 6 is a detail in section of a portion of the feeding mechanism for the wheel carriage; and

Fig. 7 is a front elevation of the wheel carriage showing the feeding mechanism for the cylindrical grinding machine.

The two main types of grinding machines in this art are to be differentiated by the fact that in one the work supporting table is reciprocated past a rotating wheel which is fed transversely into the work, while the other type involves mechanism for reciprocating the wheel past a stationary work support, the wheel being similarly fed towards the work.

In accordance with my invention, I propose to reciprocate both the wheel carriage and the work table past each other in order to double the speed heretofore considered feasible. As shown in Figs. 1, 2 and 3, my invention may be applied to a surface grinder which involves a base 10 having a work supporting table 11 slidably mounted on a parallel V-way 12 and flat way 13, as is usual in this art, and a wheel carriage 15 mounted to slide transversely relative to the path of the work carriage on suitable V and flat ways 16 and 17 respectively, these ways being in the upper surface of a wheel carrying table 18 mounted to reciprocate parallel with the work table on cooperating parallel V and flat ways 19 and 20 formed in the base of the machine and the under side of the table, as shown in Fig. 2.

The grinding wheel 21 mounted on a spindle 22 supported horizontally in suitable bearings in the wheel carriage 15 may be driven by suitable means, such as an electric motor 23 mounted on the wheel carriage 15 and connected by a belt with a pulley 24 on the wheel spindle, the details of this part of my mechanism being constructed in accordance with well known practice in this art.

In order to drive the work table and the wheel supporting table simultaneously in opposite directions, I may provide a mechanism such as illustrated in Figs. 2 and 3

comprising the drive shaft 30 suitably mounted in the base of the machine and adapted to be driven from any external source of power, as indicated by the three step pulley 31. A clutch 32 of suitable construction may be provided to disconnect the shaft 30 from the pulley shaft 33. The form illustrated involves a member 34 keyed to shaft 33 and having clutch teeth thereon and 10 a shiftable clutch member 35 slidably keyed to the shaft 30 for engagement with and disengagement from the clutch teeth of member 34, this slidable movement being caused by a yoke 36 engaging the sides of a groove 37 15 in the clutch member 35. This yoke may be operated by suitable mechanism such as a handle 38 on the outside of the machine fixed to the member 39 pivoted in the wall of the machine and rigidly connected with 20 the yoke member 36.

A reversing clutch mechanism of suitable type, such as may be found in my prior Patent No. 762,838 dated June 14, 1904, is interposed between the shaft 30 and the drive 25 shaft 42 of an easy start driving mechanism. This driving mechanism, as fully disclosed in my prior Patent No. 1,261,158 dated April 2, 1918, may involve a screw threaded member 44 slidably and rotatably mounted 30 on the shaft 42 and adapted to be driven by two friction driving members 45 and 46 fixed to the shaft 42. These members have conical surfaces adapted to engage similarly shaped reverse cones in the cam members 47 35 and 48 mounted on the ends of the worm member 44. The shaft 49 is driven by the worm 44 through the intermediate worm gear 50 on shaft 49 which meshes with the worm, and this gear, upon each reversal in 40 direction of motion, is given an easy start by sliding the worm longitudinally of its axis, in accordance with predetermined cam curves. To this end the members 47 and 48 are provided with cam surfaces 51 and 52 45 which are engaged by cam rollers 53 and 54 mounted on the cone driving members 45 and 46 to rotate with the shaft 42. It is evident therefore that when the shaft 42 starts to rotate in the direction indicated by 50 the arrow in Fig. 3, the roller 53 will climb up the cam path on the member 47 and so move the worm 43 longitudinally of its axis at a gradually increasing rate, as determined by the shape of the cam path. The worm 55 having its pitch suitably proportioned for this purpose will not rotate during this starting period, but will serve as a rack bar to turn the wheel 50 until the tables have attained full speed and the friction drive between the members 45 and 48 will have 60 started the worm to rotating, this transition in driving motion taking place easily since the worm is light and will not cause material shock when started to rotate. The shaft 49 in the embodiment illustrated has two

gears 55 and 56 mounted to rotate therewith, the gear 55 meshing with a rack 57 on the under side of the wheel table 18. In order that the work carrying table may reciprocate in an opposite direction at the same time, an intermediate gear 58 is interposed 70 between the gear 56 and the rack 59 on the work table 11.

Suitable mechanism is also provided to operate the reversing clutch and provide a 75 variable traverse for the tables. The form shown comprises dogs 60 and 61 slidably mounted in a T-slot 62 on the wheel carriage 18 for adjustment to any desired position. These dogs, which may be held in position 80 by suitable clamps, cooperate with the lever 63 pivoted on the machine and engaging the reciprocable member 64 of a load and fire mechanism as fully shown in my prior Patent No. 762,838. As illustrated in Fig. 3, 85 this part 64 is connected through springs 65 and 66 with a member carrying the yoke 67 which engages the slidable clutch member 68 of the reversing mechanism. This member 68 is keyed to the shaft 30 and is adapted 90 to be thrown into engagement with clutch teeth on the gears 69 fixed to shaft 30 or 70 fixed on shaft 42. Hence, gear 70 is driven either by the gear 69 through the intermediate gear 71 or directly from the reciprocable clutch member 68. It of course is 95 obvious that any suitable reversing mechanism may be substituted for the one herein illustrated. It will therefore be seen that when the shaft 33 is driven, the tables 11 and 18 will be reciprocated in opposite directions past each other until one of the dogs 60 or 61 strikes the lever 63 and throws the load and fire mechanism to reverse the direction of travel, whereupon the table will be 100 given an easy and gradual start in the opposite direction, due to the influence of the cam members of the reversing mechanism.

In the forms illustrated in Figs. 4 to 7 inclusive, I have shown the same idea as 110 applied to a cylindrical grinding machine in which the wheel axis is parallel with the work axis and the work is rotatably mounted on suitable head and tail stocks 80 and 81 adjustably positioned on the work carrying table 82 which is pivotally mounted on the lower table 11, all in accordance with constructions well known in this art. The driving mechanism for this construction may also be made as illustrated in Fig. 3. 115 For the sake of clarity of illustration, the headstock is shown as being driven by a belt 83 from an overhead drive, but I may obviously employ any suitable mechanism for 120 rotating the work in accordance with my 125 patents heretofore granted on self-contained grinding machines.

In order to feed the wheel into the work, I may provide various types of wheel feed. A simple form for the cylindrical grinding 130

machine in which the wheel carriage is fed in toward the work by hand without the use of automatically actuated devices is shown in Figs. 5, 6 and 7, according to which I provide a screw 84 mounted in suitable bearings transversely of the carriage 18 in engagement with a threaded half nut 85 rigidly carried on the bottom of the wheel carriage 15 and preferably, as shown in Fig. 6, beneath the V-way, the support 87 for this half nut extending through a slot in the V-way of the carriage 15. The screw 84 is rotated by means of a bevel gear 88 on the end of the spindle engaging a bevel gear 89 on the cross shaft 90 mounted on the table 18. This shaft 90 is in turn rotated through bevel gears 91 and 92, the latter being on the lower portion of an upright shaft 93 supported by a bracket 95 from the table 18, the shaft 93 being adapted to be turned to a desired extent by the hand wheel 94.

An automatically actuated cross feed mechanism may be provided if desired and, as shown in Figs. 1 and 2, the feed mechanism illustrated in my prior Patent No. 1,197,700 dated September 12, 1916, may be adapted for use on the surface grinding machine. This mechanism comprises a gear 100 on the end of shaft 84 which meshes with gear 101 on the shaft 102. A ratchet wheel 103 fixed to the shaft 102 is actuated by a pawl 104 mounted to swing about the shaft 102. This pawl is moved to pull downwardly on the teeth of the ratchet wheel by means of a pitman 105 eccentrically pivoted on the wheel 106 which is rotated by means of a rack and pinion mechanism. The rack 107 engaging the pinion 108 fixed to the wheel 106 is reciprocated by means of a lever 109 pivotally mounted on the carriage 18. This lever carries an arm 110 having a member 111 slidably mounted on the arm and to which the rack member 107 is hinged. This lever 109 is adapted to be swung to and fro by means of dogs 112 and 113 adjustably mounted in the T-slot 114 on the machine base, all as will be more clearly understood from a perusal of my prior specification. According to this construction the wheel is fed a predetermined amount toward the work upon each reversal in direction of traverse of the wheel carriage 18 due to one of the dogs striking the lever 109 and thereby actuating the pawl 104.

The operation of my grinding machine is obvious from the above disclosure, it being apparent that when the shaft 30 is rotated, the tables 11 and 18 will be reciprocated in opposite directions past each other until one of the dogs 60 or 61 strikes the lever 63 and throws the load and fire mechanism to reverse the direction of travel, whereupon the table will be given an easy and gradual start in the opposite direction, due to the influ-

ence of the cam members of the reversing mechanism.

Having thus described my invention, what I claim as new and desire to secure by Letters Patent is:

1. A grinding machine comprising a base having parallel ways thereon, two tables mounted on said ways for reciprocation past each other, one of said tables constituting a work support, a wheel slide on the other table which is reciprocable transversely thereof, a rotatable grinding wheel carried on said slide, a cross feed mechanism to move the slide and feed the grinding wheel relative to the work, a single driving and reversing mechanism to reciprocate the tables in opposite directions past each other simultaneously and means including adjustable dogs actuated by one of said tables to operate said mechanism and reverse the direction of movement of both tables.

2. A grinding machine comprising a base having parallel ways thereon, two tables mounted on said ways for reciprocation past each other, one of said tables constituting a work support, a wheel slide on one table movable transversely thereof, a rotatable grinding wheel carried on said slide, a cross feed mechanism to feed the grinding wheel into the work and means including a driving and reversing mechanism operatively connected to simultaneously reciprocate the grinding wheel table and the work table in opposite directions to increase the relative traverse speed between the grinding wheel and work.

3. A grinding machine comprising a base having parallel ways thereon, two tables mounted on said ways for reciprocation past each other, one of said tables constituting a work support, a wheel slide on the other table movable transversely thereof, a rotatable grinding wheel carried on the wheel slide, a cross feed mechanism to feed the grinding wheel into the work to size the same, means including a single reversing mechanism operatively connected to both of said tables to simultaneously reciprocate the grinding wheel and work in opposite directions through a variable length of stroke to increase the relative feed between the grinding wheel and work.

Signed at Worcester, Massachusetts, this 5th day of Nov. 1920.

CHARLES H. NORTON.
